UNITED STATES PATENT OFFICE.

WILLIAM W. JACKSON, OF RENOVO, PENNSYLVANIA.

UMBRELLA LOCK-BOX.

1,160,081.

Specification of Letters Patent.

Patented Nov. 9, 1915.

Application filed April 7, 1914. Serial No. 830,205.

To all whom it may concern:

Be it known that I, WILLIAM W. JACKSON, a citizen of the United States, residing at Renovo, in the county of Clinton and State 5 of Pennsylvania, have invented certain new and useful Improvements in Umbrella Lock-Boxes; and I do hereby declare the following to be a full, clear, and exact description of the invention, such as will enable others 10 skilled in the art to which it appertains to make and use the same.

This invention relates to umbrella lock boxes, designed for use in hotels, restaurants, public buildings and other places, to 15 prevent the loss of umbrellas, either by theft or by mistake, and one of the principal objects of the invention is to provide a device of comparatively simple construction which will hold an umbrella or cane against withdrawal by an unauthorized person not provided with the key of the box.

Another object of the invention is to provide a simple device for holding an umbrella or cane against withdrawal until the proper 25 key has been inserted to release the umbrella from the lock.

These and other objects may be attained by means of the construction illustrated in the accompanying drawings, in which,

30 Figure 1 is a side elevation of an umbrella lock box made in accordance with this invention, Fig. 2 is a plan view of the same with the top or cover removed to show the interior construction, portions of which are 35 shown in section and taken on the line 2—2 of Fig. 1, Fig. 3 is a vertical section taken from front to rear of the box and showing the key in place before the umbrella is locked to the box, Fig. 4, is a sectional view 40 taken on the line 4—4 of Fig. 2 with the cover in place and the key inserted in the cover, and Fig. 5 is a front end elevation of the device.

45 Referring to the drawings, the numeral 1 designates the back or rear portion of the box, 2 is the bottom, 3 are the sides, 4 is the front and 5 is the top or removable cover of the box. The box or casing is secured to the wall by means of suitable plates or 50 brackets having lugs secured to a wall or support, said lugs 7 being connected to the wall by means of screws 8 and provided with outwardly projecting portions 9 con-

nected by a cross plate 10 at the sides of the box, said members being formed on the base 55 plate 11 which lies flat against the face of the wall and holds the box spaced from the wall a sufficient distance to permit its operation. The box is secured at the required height from the floor to lock an umbrella 60 handle near the hand hold thereof.

The box or casing is provided with a metal lining 12. Mounted to slide in the box is a block 13, said block having projecting studs 14 which extend through the back portion 1 of the casing, and are provided with encircling springs 15 which exert their expansive force in pushing the block 13 toward the front wall of the box or casing. The block 13 is provided with two vertical sockets or apertures 16, in the bottoms of which are seated spiral springs 17. Resting upon the upper ends of the spiral springs 17 are pins or bolts 18 which normally project above the upper face of the block 13, as 70 shown more clearly in Fig. 4.

Connected centrally to the front side of the block 13 is a threaded locking bolt 19 which is mounted in a sleeve 20 secured to the front portion 4 of the box. Connected 80 to the outer end of the bolt 19 is a ring 21, and mounted to slide upon the ring 21 are the two umbrella clamp members 22 provided with semi-circular jaws which when brought together will encircle the handle of 85 an umbrella. The front portion 4 of the box is provided with a vertical slot 23 to permit the flanges 24 on the clamp members 22 to move inward and outward, and a transverse slot 25 for the ring 21. Connected to the inner rear portion of the block 13 is a key securing device 26 provided with 90 forwardly projecting points 27 adapted to project into a perforation 28 in the key 29 when the latter is held in the box before the 95 umbrella is connected to the jaws 22.

The bolt 19 may extend entirely through the block 13 and may project through the back member 1 of the box or casing. Connected to the inner end of the bolt 19 is a 100 shank 30 carried by a sliding member 31 mounted in a guide member 32 secured at the side of the box, said member 31 being provided with an outwardly projecting arm 33 having a knob or ball 34 secured to its 105 outer end.

Connected underneath the top 5 of the box is a wedge shaped abutment 35, which is connected to the cover 5 by means of a screw 36.

5 When the umbrella handle is placed between the two clamp members 22 and they are pushed inwardly by means of the sliding member 31 which is operated by the hand grasping the knob 34 and pushing backward 10 against the tension of the springs 15, the pins 18 will engage the rear wall of the abutment 35, and the point 27 will be withdrawn from the aperture 28 of the key, thus permitting the latter to be withdrawn.

15 Each box is provided with a number plate 8^a and the key is also numbered to correspond. A key-hole slot 37 is formed in the top 5 to receive the key 29, and when the umbrella is locked in place, the pins 18 are 20 in line with the key-hole 37, and are held in their rearmost position by means of the abutment 35. The key 29 may be provided with various forms of projections of different degrees of lengths and contours, and 25 when the right key is forced into the key-hole the pins 18 will be pressed down within the sockets 16 until they pass underneath the inclined portion of the abutment 35 to permit the umbrella to be removed from the 30 members 22, as will be evident.

From the foregoing it will be obvious that an umbrella lock box made in accordance with this invention may be manufactured at low cost, is reliable and efficient for its purpose, and cannot be unlocked except by the key intended or made for that particular box.

Various changes may be made in the details of construction without departing from 40 the spirit and scope of the invention as defined in the claims.

What is claimed is:—

1. An umbrella lock box comprising a casing having a front and a rear wall, top, bottom, and side walls, means to secure said casing spaced from a support, a block slidably mounted in said casing, a longitudinal bolt carried by said sliding block, said bolt being adapted to extend through the front and 45 rear walls of said casing, a horizontal ring secured to the outer end of said bolt, a pair of jaws having integral vertical flanges extending rearwardly therefrom and pivotally secured to said horizontal ring, said front 50 wall being provided with a vertical slot and a horizontal slot bisecting said vertical slot, means to draw said bolt inwardly, the vertical flanges on said pivoted jaw and the horizontal ring being adapted to engage the 55 slots in the front wall whereby said jaws are prevented from being opened, and means to lock said sliding block.

2. An umbrella lock box comprising a casing having a front and a rear wall, top, bottom, and side walls, means to secure said

casing spaced from a support, a block slidably mounted in said casing, a longitudinal bolt carried by said sliding block, said bolt being adapted to extend through the front and rear walls of said casing, said rear wall 70 having a pair of apertures, a pair of rearwardly projecting studs secured to said sliding block and adapted to extend through said apertures in said rear wall, a coil spring surrounding each stud and having one end bearing against said rear wall, and the opposite end against said sliding block whereby said bolt is normally held forward, a horizontal ring secured to the outer end of said bolt, a pair of jaws having integral vertical flanges extending rearwardly therefrom, and pivotally connected to said horizontal ring, said front wall being provided with a vertical slot and a horizontal slot bisecting said vertical slot, a means to draw said bolt inwardly, the vertical flanges on said pivoted jaw and the horizontal ring being adapted to engage the slots in said front wall whereby said jaws are prevented from being opened, and means to lock said sliding block. 80

3. An umbrella lock box comprising a casing, having a front, rear, top, bottom and side walls, a block slidably mounted in said casing, spring pressed pins secured on the upper face of said block, a longitudinal bolt carried by said block, means to draw said bolt rearwardly, said bolt being adapted to extend through the front and rear walls of said casing, an abutment secured to the under face of said top wall of the casing, the under face of said abutment being inclined, said pins being adapted to engage the inclined face of said abutment when the bolt is being drawn inwardly and adapted to engage the rear face of said abutment 90 when the bolt is in operative position, whereby said bolt is prevented from being moved outward, a key adapted to press said pins downward, and means carried by said sliding block to prevent the withdrawal of said key when the bolt is in operative position, and means carried by the outer end of said bolt to engage the umbrella. 95

4. An umbrella lock box comprising a casing having a front, rear, top, bottom, and side walls, a block slidably mounted in said casing, spring pressed pins secured on the upper face of said block, a longitudinal bolt carried by said block, means to draw said bolt rearwardly, said bolt being adapted to extend through the front and rear walls of said casing, an abutment secured to the under face of said top wall of the casing, the under face of said abutment being inclined, said pins being adapted to engage the inclined face of said abutment, when the bolt is being drawn inwardly and adapted to engage the rear face of said abutment when the bolt is in operative position whereby said bolt is prevented from being moved outward, 115

a key adapted to press the spring pressed pins downward having an aperture, an upwardly extending arm secured to said sliding block, an angular extension on said arm, 5 said extension being adapted to extend through the aperture in said key when said bolt is in operative position whereby said key is prevented from being removed, and

means carried by the outer end of said bolt to engage the umbrella. 10

In testimony whereof I affix my signature in presence of two witnesses.

WILLIAM W. JACKSON.
